UNITED STATES PATENT OFFICE.

ERNEST W. KLEIN, OF LOS ANGELES, CALIFORNIA.

MUSICAL TOY.

Application filed April 23, 1921. Serial No. 463,784.

To all whom it may concern:

Be it known that I, ERNEST W. KLEIN, a citizen of the United States, residing at Los Angeles, in the county of Los Angeles 5 and State of California, have invented new and useful Improvements in Musical Toys, of which the following is a specification.

This invention is a toy forming a whistle adapted to be held in the mouth and blown 10 through the nose, the improved construction providing in a device of this character, improved means for properly positioning the whistle without necessitating employment of the hands, and also affording a construction in which the volume of sound produced will be amplified.

The invention will be readily understood from the following description of the accompanying drawings, in which:

20 Figure 1 is a vertical section through a device constructed in accordance with the invention and showing the same in operative position.

Fig. 2 is a rear elevation of the whistle.

25 Fig. 3 is a side elevation of the same.

Fig. 4 is a front view of the device.

The whistle is preferably formed of sheet metal and includes a flaring portion 1 received over the base of the nostrils and having 30 a depending extension 2 fitting against the upper lip. This extension terminates in a rearwardly bent annular member 3 which is received in the mouth and is preferably closed at its inner end, as shown at 4, and 35 provided at its outer end with a flaring mouth 5 in order to form a horn-like structure.

The flaring portion of the device is provided with an opening 6 in alignment with 40 the nostrils, and said opening communicates with an air chamber 7 formed upon the front of the structure and extending from the plate 1 over the extension 2 and inwardly along the roof of the horn 3 so as 45 to open into said horn through a restricted aperture 8. The roof of the horn is provided with an opening 9 adjacent the restricted aperture 8 so that air passing through the passageway 7 and its restricted 50 opening will impinge against the edge of opening 9 for producing a whistling sound.

In order that the device may be held in position without employing the hands, a lip 10 is preferably formed upon the exterior of 55 horn 3 and at the front of opening 9, so that when the horn is received in the mouth the

upper teeth may be engaged over said lip. In order to more positively position the device by means of the teeth, a transverse bead 12 is provided upon the exterior of the base 60 of horn 3 in such position that the lower front teeth may be received against the rear of said bead.

It will be noted that the construction, as thus set forth, provides positive means for 65 properly positioning the horn 3 within the mouth, since the upper teeth bear against the front of lip 10, while the lower teeth impinge against the rear of bead 12, and as a consequence the horn is held in the mouth 70 by a binding engagement adapted to prevent displacement thereof, and also affording means for properly positioning the upper portion of the device over the nostrils.

It will also be noted that the provision of the lower portion of the device as a horn structure, will provide means for amplifying the sounds produced by the whistle.

Various changes may be made without departing from the spirit of the invention as claimed.

What is claimed is:

1. A whistle comprising a member having an opening for fitting the nose and also having a depending portion received in the mouth, said depending portion having an opening provided with a lip adapted to be engaged by the upper teeth, and said depending portion also having a protuberance 85 upon the underside forming an abutment element impinged by the lower teeth.

2. A whistle comprising a member having an opening for fitting the nose and also having a depending portion received in the 95 mouth and forming an annular horn structure.

3. A whistle comprising a member having an opening for fitting the nose and also having a depending portion received in the 100 mouth and forming an annular horn structure, said horn structure having an opening provided with a lip adapted to be engaged by the upper teeth and also having a protuberance upon the underside forming 105 an abutment element impinged by the lower teeth.

In testimony whereof I have signed my name to this specification.

ERNEST W. KLEIN.
